(57) **CLAIM**

The ornamental design for a radio transmitter unit, as shown and described.

DESCRIPTION

FIG. 1 is a front view of the radio transmitter unit embodying the design;

FIG. 2 is a rear view thereof;

FIG. 3 is a right-side view thereof;

FIG. 4 is a left-side view thereof;

FIG. 5 is a top view thereof;

FIG. 6 is a bottom view thereof; and,

FIG. 7 is a front and left-side perspective view thereof.

The broken lines in FIGS. 1 to 7 show elements which may be part of the environment of the design and form no part of the design as claimed.

1 Claim, 5 Drawing Sheets**FIG. 1**

FIG. 2

FIG. 3**FIG. 4**

FIG. 5**FIG. 6**

FIG. 7
